UNITED STATES PATENT OFFICE.

MILLAN H. HOLMES AND WILLIAM A. MATHESON, OF CHICAGO, ILLINOIS.

WALL-BED.

1,037,911.

Specification of Letters Patent. Patented Sept. 10, 1912.

Application filed October 7, 1911. Serial No. 653,369.

To all whom it may concern:

Be it known that we, MILLAN H. HOLMES and WILLIAM A. MATHESON, citizens of the United States, residing at Chicago, in the county of Cook and State of Illinois, have invented certain new and useful Improvements in Wall-Beds, of which the following is a specification.

Our invention relates to wall beds, and refers particularly to various improvements which tend to give the beds superior operating qualities.

The wall beds which form the subject-matter of our invention are of the type which fold upwardly into a suitable recess, and may be lowered for use.

It is one of the objects of our invention to provide means by which in folding the bed upwardly into its closed position or lowering it into the position in which it is used, the bed may be checked so that there will be no liability for the bed to violently come in contact with the casing, in the first case, or in contact with the floor in the second case. We accomplish this result by means of an improved check, as will be described in detail hereafter.

A further object of our invention consists in the use of an escutcheon plate on the bottom of the bed, this plate being made in such manner that when the bed is raised into its closed position the legs automatically move into the slots within the escutcheon plates. In this manner a very pleasing appearance is presented on the front of the bed, when in its vertical position.

A further object of our invention consists in the use of a weight bracket which is adjustably attached to the pivot bracket of the bed so that by placing the weight bracket in the proper position the desired amount of force may be obtained for moving the bed from its lowered operative position to its closed position.

A further object of our invention consists in the use of weights of a special form. We have found that it is particularly advantageous to use weights which are curved on their ends so that a desired position of the center of gravity is obtained, and the weights readily clear the floor when the bed is closed.

A still further object of our invention consists in the use of pivotal means for supporting the head piece of the bed on the end

piece so that the head piece always remains in a vertical position no matter in what position the bed itself may be placed. This construction is of particular advantage inasmuch as it allows the use of a much higher head piece than it has formerly been possible to employ.

A still further object of our invention consists in the provision of readily operable locking means by which the bed is locked in its lowered position, and all possibility of its automatically closing is avoided until the locking means has been released.

A still further object of our invention consists in the use of a special form of leg, which is so constructed that when the bed is brought to its lowermost position the end of the leg slips into a recess and is securely locked in position, while at the same time swinging of the leg beyond a predetermined position is avoided by means of a suitable abutment member.

These and other advantages of our invention will be more readily understood by reference to the accompanying drawings, in which—

Figure 1 is a longitudinal section taken on the line 1—1 of Fig. 2, the bed also being shown in dotted lines in its raised position; Fig. 2 is a transverse section taken on the line 2—2 of Fig. 1; Fig. 3 is a front elevation showing one of the escutcheon plates used on the bottom of the bed; Fig. 4 is an elevation of the pivot casting attached to the side wall of the recess in which the bed operates; Fig. 5 is an enlarged transverse section showing the locking mechanism used for the bed; and Fig. 6 is an enlarged fragmentary side elevation and partly sectional view showing one of the legs and the abutment member and locking means for holding the same in position.

The bed of our construction is designed to operate within a recess having the side walls 10, the bottom 11 and the rear wall 12. To each of the side walls 10 is attached a pivot bracket 11^a, having therein the circular recess 12^a. One of these brackets is also constructed with a horizontal locking rib 13, the object of which will be explained hereafter.

The bed itself consists of a bottom 14, of wood or other similar material, in which a mirror 15^a may be mounted if so desired.

Attached to the bottom 14 are a pair of escutcheon plates 15, each of which has the knob 16 by which the bed may be pulled into its lowered position. Each escutcheon plate 15 has a slot 17 adapted to receive the leg 18. Attached to the bottom 14 and registering with the slot 17 in each of the escutcheon plates 15 is a bracket 19, having the abutment member 20 and the locking projection 21. This bracket is also provided with the side plate 22 having thereon the pivot or pin 23. The leg 18 has at its upper portion the elongated slot 24, through which the pivot or pin 23 passes. It will be evident that while the bed is being lowered the leg 18 will, on account of its free rotation on the pivot 23, always occupy a vertical position, and, finally, just before the leg has struck the floor the parts will be as represented in full lines in Fig. 6. It will be impossible for the leg 18 to swing to the right farther than indicated in Fig. 6, inasmuch as the projection 25 of the leg 18 will come in contact with the abutment member 20. As the bed continues to be lowered the bracket 19, the bottom 14 and the escutcheon plate 15 will move into positions indicated in dotted lines, and the locking projection 21 will descend and engage one side of the projection 25 of the leg 18 so that the leg will be securely locked in position and can not move.

Attached to the foot of the bottom 14 are a pair of foot brackets 26, between which extends the end rail 27, preferably in the form of an angle iron, while the foot piece 28 also extends between the foot brackets 26.

Mounted at the two sides of the head end of the bottom 14 are the two pivot brackets 29, each of which is provided with a lug 30 projecting into the corresponding recess 12^a of the brackets 11^a. Securely fastened within suitable concave grooves 31 of the pivot brackets 29 are the two side rail tubes 32, these side rail tubes also being fastened to corresponding recesses in the foot brackets 26. Extending between the pivot brackets 29 is the end rail 33, preferably in the form of an angle iron, and also fastened to the two pivot brackets 29 is the metallic end 50 frame 34, which, also, preferably consists of angle irons. A wood panel 35 extends over the head end of the bed, and is suitably fastened to the end frame 34 and the end rail 33.

Fastened to each of the pivot brackets 29 is a weight bracket 36, having the projections 37 and 38. The projection 37 is provided with the slot 39, while the projection 38 is provided with the slot 40. A bolt 41 passes through the slot 39 and bolts 42 pass through the slot 40. It will thus be evident that by loosening the bolts 41 and 42, each of the weight brackets 36 may be adjusted to a desired position. Extending between the weight brackets 36 are the weight rods 43, on which the weights 44 may be mounted. These

weights, as clearly shown in Fig. 1, are preferably curved at one end so that they readily clear the floor when the bed is raised from its horizontal to its vertical position, and are provided with the slots 45, for attachment 70 to the weight rods 43. When the bed bottom 14 is in a horizontal position the center of gravity of the weights 44 is preferably in a slightly lower plane than that of the pivot 30, so that when the bed bottom is raised to a vertical position this center of gravity will be carried slightly to the right of the vertical plane of the pivot 30, thereby causing the weights to exercise a certain checking effect in the last part of the closing movement of the bed. If it is desired to vary the position in which the bed comes to rest in its substantially vertical position, the weight brackets may be suitably adjusted to obtain the desired result. 85

One of the pivot brackets 29 is provided with a recessed cap plate 46, within which the locking member 47, pivotally mounted at 48, is adapted to move, the locking member 47 being normally forced to the left, as indicated in Figs. 2 and 5, by means of the spring 49 mounted on the rod 50. The locking member 47 is provided with a projection 51, having near its end the pin 52, which has slotted engagement with the lever 53 mounted on the rod 54, which extends through one of the side rail tubes 32, and is provided at its end with the handle 55. It will now be apparent that as the bed is lowered into its final position the locking member 47 will move upwardly until it passes the locking rib 13, and will then be moved into the positions indicated in Figs. 2 and 5, on account of the pressure of the spring 49. In order to release the locking member 47 by 105 moving it to the right it is only necessary to turn the handle 55 in a clock-wise direction, whereby the locking member 47 will be moved to the right and the bed may be raised. 110

Pivottally connected to the inner corner of the recess within which the bed operates is the rod 56 of the check 57. The opposite end of this check is provided with the slot 58, within which the pin 59, mounted on the weight bracket 36, is adapted to operate. The check 57 has the cylinder 60, which is mounted integrally with the rods 61, while on the end of the rod 56 is mounted a piston movable within the cylinder 60. 115

To the upper portion of the frame 34 are attached the bearings 62, through which passes the rod 63 of the head piece 64, this head piece being suitably connected with the side walls 10 of the recess so that it will always maintain a vertical position. For the sake of simplicity this connection has not been shown in the drawings. 125

Attached to the bottom 14 is a hood, which is preferably of wood, and consists of a 130

member 65 and a member 66. These members coöperate to prevent the weights from being visible when the bed is either in its lowered or its upright position.

Having thus described the various parts which are used in our invention, the operation of the same may now be readily understood: Let us assume that the bed is in its lowered position. When it is desired to raise the bed, the handle 55 is turned, whereby the locking member 47 is released from the locking rib 13. The bed may now be raised, and as this happens the legs 18 first assume the position shown in full lines in Fig. 6, and then swing around into the recesses 17 of the escutcheon plates 15 when the bed is in its final closed position. As the bed is swung up on the lugs 30 as axes the weight brackets 36 and the weights 44 move down until they finally assume the positions shown in dotted lines in Fig. 1, while the weight casing 65 moves up into the position shown in dotted lines. If it is found that the counter-balancing action of the weights 44 is too great, the weight brackets 36 may be slightly lowered, thereby correspondingly lowering the center of gravity of the weights 44, whereas, if it is found that the action is too little, they may be correspondingly raised. When the closing action starts the pin 59 on one of the weight brackets 36 moves down within the slot 58 until it strikes the lower portion of this slot. After this happens, the cylinder 60, through the instrumentality of the rods 61, is moved toward the pivotal connection of the rod 56, and, on account of the construction of the check, no resistance is offered to this movement. When the bed approaches its upper position the pin 59 moves out through the slot 58 until it encounters the outer end of this slot. The cylinder 60 is then moved out, but, on account of the construction of the valves in the piston within the cylinder 60, resistance is now offered to the outward movement of the cylinder 60, and the bed is checked in its closing until finally it reaches the upright position indicated in dotted lines in Fig. 1. On the other hand, when the bed is closed and it is desired to open it into operative position, the knobs 16 on the escutcheon plates 15 are taken hold of and the bed is pulled down against the slight resistance offered by the counter-balancing weights 44. This reverse motion of the bed will cause the check to act in a similar manner to that already described but with the motion of these several parts occurring in reverse order. When the bed has reached a position slightly above the horizontal, the counter-balancing action of the weights 44 exactly neutralizes the tendency of the bed frame to move down, so that the bed is brought to its final open horizontal position by being manually

pressed down. In this way the bed is checked both near its closing point, when it is raised, and near its final opened position when it is lowered; but in moving from one position to the other the initial part of the movement is always free. The two legs 18 keep in their vertical positions as the bed is lowered, and, finally, are locked against movement, in the manner heretofore described. When the bed reaches its final lowered position the locking member 47 snaps into engagement with the locking rib 13, and it is impossible to raise the bed until this locking member is released.

As previously described, when the bed is opened and lowered the head piece 64 always retains its vertical position, inasmuch as the rod 63 is rotatable within the bearings 62.

It will be apparent to those skilled in the art that many changes could be made in the detailed construction of the various parts which we have described without departing from either the spirit or scope of our invention.

What we claim is:

1. In a folding bed, a pivotally mounted counter-balanced frame, and a single device for checking the movement of the frame as it approaches its open and its closed positions, said device being inactive in both of the extreme positions of the bed frame, substantially as described.

2. In a folding bed, a pivotally mounted counter-balanced frame, and a single fluid controlled device for checking the movement of the frame as it approaches its open and its closed positions, said device being inactive in both of the extreme positions of the bed frame, substantially as described.

3. In a wall bed, the combination of a pivotally mounted frame, counter-balancing means for said frame, pivoted checking means attached to said frame, said checking means being provided with a slot, and means on said frame for engaging said slot whereby the checking operation is performed only as said frame approaches the end of its opening and closing movements, substantially as described.

4. In a wall bed, the combination of a frame, a pair of supporting members, means for pivotally mounting said frame on said supporting members, counter-balancing means attached to said frame and tending to move the latter into an upright position, and checking means having slotted connection with said frame, said checking means comprising a relatively movable cylinder and a piston therein which have free movement in one direction and a restricted movement in the opposite direction, said slotted connection rendering said checking means operative only when said frame approaches the end of its movement while being raised or

lowered into position, substantially as described.

5. In a wall bed, the combination of a bed frame, means for pivotally supporting said frame, an adjustable weight bracket mounted on said frame, and a counter-balancing weight carried by said weight bracket, substantially as described.

6. In a wall bed, the combination of a bed frame, means for pivotally supporting said frame, counter-balancing means normally tending to raise the bed into vertical position, means for automatically locking said frame when in its horizontal position, and means at or near the foot of the bed for releasing said locking means, substantially as described.

7. In a wall bed, the combination of a bed frame having a tubular side rail, means for pivotally supporting said frame, counter-balancing means mounted on said frame, a spring-controlled lock carried by said frame, a cooperating locking member stationarily mounted with respect to said

frame, whereby the frame will be automatically locked when in its horizontal position, a controlling rod for operating said lock and extending through said side rail, and means for manually operating said controlling rod, whereby the lock may be released and the bed may be raised from a horizontal to a vertical position, substantially as described.

8. In a wall bed, the combination of a movable bed frame, a wall bracket having a locking surface, a spring controlled member pivotally mounted on said frame and adapted to form locking engagement with the locking surface of said bracket when said frame is in its horizontal position, and means for releasing said member, whereby said frame may be moved, substantially as described.
